J. N. BORROUGHS

MACHINE FOR FOLDING TOWELS

Filed Aug. 31, 1920

By Harry P. Schroeder
Attorney

UNITED STATES PATENT OFFICE.

JOSEPH N. BORROUGHS, OF OAKLAND, CALIFORNIA.

MACHINE FOR FOLDING TOWELS.

Application filed August 31, 1920. Serial No. 407,263.

To all whom it may concern:

Be it known that I, JOSEPH N. BORROUGHS, a citizen of the United States, residing at Oakland, in the county of Alameda and State of California, have invented certain new and useful Improvements in Machines for Folding Towels, of which the following is a specification.

My invention relates to machines for folding soiled towels so that they may be washed.

In washing very long towels in a washing machine, they often become so tangled, and torn, that they are useless. The object of my invention is to provide a machine which will quickly and efficiently fold the towel in a compact bundle. The towel after being folded is securely pinned at both edges and placed in the washing machine for washing.

These objects are accomplished by the particular structure and arrangement of parts illustrated in the accompanying drawing, which forms a part of this specification, and in which:—

Figure 1 is a transverse sectional view of my towel folding machine.

Figure 2 is a top plan view thereof.

Referring more particularly to the drawing, the numeral 1 indicates a frame having horizontal members 2 and 3. A roller 4 is journaled in bearings secured to the members 2 and 3. A smaller roller 5, adapted to contact with the roller 4, is journaled in arms 6 and 7, which are journaled in bearings secured to the members 2 and 3. Springs 8 on the arm journals create a pressure between the rollers 4 and 5.

A tubular pendulum 7^a is journaled on trunnions 8^a in the members 2 and 3, below the contact point of the rollers 4 and 5.

A shaft 8' is journaled in the members 2 and 3 forwardly of the roller 4. A pulley 9 is secured to one end of the shaft 8', so that power may be applied there to rotate said shaft. To a crank 10 in the shaft 8' is secured a pitman 11, which is also secured to the pendulum 7, to transmit a vibratory motion thereto. A chain 12 travels over sprockets 13, on the shaft 8, and 14 on the shaft of the drum 4, thereby rotating said drum.

The towel is fed by the rollers 4 and 5 and down thru the oscillating pendulum 7, which folds the towel upon itself at the beginning of each oscillative stroke. When the whole towel is folded the edges are pinned together and the towel is placed in a washing machine for washing.

Having described my invention I claim:

A machine for folding towels including a frame, a tubular pendulum pivoted at its upper end to the upper part of said frame, a shaft journaled on the upper part of said frame, a feed roller secured on said shaft with its periphery in alignment with the upper end of said tubular pendulum, a sprocket on said roller shaft, a crank shaft journaled in the upper part of said frame, a crank on said crank shaft, a pitman connecting said crank and the upper part of said pendulum, a sprocket on said crank shaft, a chain extending over the sprocket on said roller shaft and said crank shaft, a pair of arms journaled on the upper part of said frame, a pressure roller engaging said feed roller by gravity directly above the upper end of said pendulum, and means whereby said crank shaft may be driven.

In testimony whereof I affix my signature.

JOSEPH N. BORROUGHS.
